G. W. KRAHMER,
CHUTE FOR LIVE STOCK.
APPLICATION FILED JAN. 4, 1918.

1,297,696.

Patented Mar. 18, 1919.

UNITED STATES PATENT OFFICE.

GEORGE WILLIAM KRAHMER, OF CYLINDER, IOWA.

CHUTE FOR LIVE STOCK.

Specification of Letters Patent. Patented Mar. 18, 1919.

1,297,696.

Application filed January 4, 1918. Serial No. 210,316.

To all whom it may concern:

Be it known that I, GEORGE W. KRAHMER, a citizen of the United States, residing at 5 Cylinder, in the county of Palo Alto and State of Iowa, have invented certain new and useful Improvements in Chutes for Live Stock, of which the following is a specification.

This invention relates to a chute for live- 10 stock and more particularly to a chute or a run-way which is adapted to be placed in a position where hogs or other live-stock may be unloaded or loaded upon stock-cars or vehicles.

15 An object of the device is the provision of a chute, the run-way of which may be varied with respect to its angular position whereby the stock may be made to climb to various heights when the bodies of the vehicles vary 20 in height.

A further object of the device is the provision of means whereby the chute may be demounted and taken apart for folding it 25 in a minimum space when not in use and which may be assembled and held together by a plurality of fastening devices with which the device is provided.

A further object of this invention is the provision of a chute which consists of comparatively few parts and is simple in construction, but durable and well adapted to withstand the rough usage to which devices 30 of this character are ordinarily subjected.

For a full description of the invention and 35 the advantages and merits thereof, reference is to be had to the following description and the accompanying drawings, wherein is illustrated the preferred form of my invention, in which:

40 Figure 1 is a side elevation.

Fig. 2 is a vertical transverse section on the line 2—2 of Fig. 1.

Fig. 3 is a fragmentary plan view.

Fig. 4 is a fragmentary section on the 45 line 4—4 of Fig. 1.

Each of the side walls A and B consist of a plurality of upright standards 1, 2 and 3, each varying in height, the standard 3 being of a greater height than the standard 1 while 50 the intermediate standard 2 is of a height greater than standard 1 and less than the standard 3. Secured to the inner sides of each of the standards is a plurality of super- 55 posed slats or guard members 4 which are disposed at an angle and extend upwardly from the standard 1 to the end standard 3.

The upper ends of each of the upright standards are connected together by the connecting bars 5 and secured to each end of each of the connecting bars is a U-shaped yoke 6 which is secured to the connecting bars 5 by the fastening elements 6'. The ends of the yokes are spaced apart from the ends of the connecting bars 5 for providing a space for the reception of the upper ends of the upright standards 1, 2 and 3. A staple 7 is secured to each standard adjacent its upper end and carries the end of a chain 8 the free end of which carries a locking pin 9 adapted to be inserted through an opening in the end 70 of the yoke and into a recess provided in the upper ends of each of the standards as shown in detail in Fig. 4 of the drawing.

The lower ends of the end standard 1 are connected together by a connecting bar 75 which is identical in construction with the connecting bar 5. Each of the other pairs of uprights 2 and 3 are connected together by connecting bars 5' which are mounted above the lower end of the uprights and 80 adapted to be adjustably mounted thereon by providing the uprights 2 and 3 with a plurality of apertures 10 which receive the ends of the locking pins 9' carried by the chains 8' the ends of each are secured to the 85 ends of the staple 7'. One end of a run-way 11, consisting of a plurality of longitudinally extending planks, rests upon the connecting bar which is secured to the lower ends of the uprights 1 while its opposite 90 end rests upon the connecting bar 5' of the standards 3'. The central connecting bar 5' is disposed beneath the center of the run-way 11. A plurality of transversely extending cleats 12 form a means for fastening the planks of the run-way together and provide suitable anti-slipping elements for preventing the animals from slipping while they are passing up the run-way. The bottom of the run-way is provided at each end 10 with a brace bar 13 which rests against the lower connecting bars for preventing the run-way from slipping off the connecting bars while the device is in use.

By virtue of the adjustable connection 1 provided by yokes and the plurality of apertures in the uprights 2 and 3, the end of the run-way may be raised or lowered for loading or unloading the live-stock upon or from vehicles of various heights. The sides of the device and the run-way together with the connecting arms may be disconnected and

taken apart for folding the device in compact space when not in use.

In reduction to practice I have found that the form of my invention illustrated in the drawings and referred to in the above description, as the preferred embodiment, is the most efficient and practicable; yet realizing that the conditions concurrent with the adoption of my device will necessarily vary, 10 I desire to emphasize the fact that various minor changes in the details of construction, proportion and arrangement of parts may be resorted to, when required, without sacrificing any of the advantages of my invention, as defined in the appended claims.

I claim:

1. A device of the character described comprising a plurality of standards, said standards including a pair of end standards and 20 a pair of opposite end standards, said first mentioned standards being of a greater length than said second mentioned standards, a pair of intermediate standards connecting bars disposed at the top of each pair of said standards and connecting their ends together, lower connecting bars connecting the lower portions of the standards together, a yoke carried by each end of said connecting bars and provided with an end aperture, a locking pin flexibly connected to each of

said standards and adapted to be extended through said aperture and into a recess formed in the end of each standard, a runway mounted on the lower connecting bars and adapted to be adjusted vertically with 25 the lower connecting bars.

2. A device of the character described comprising a plurality of standards arranged in pairs, each of said pairs being of a different length than the adjacent pair of standards, guard members secured to said standards and disposed at an angle to said standards, connecting bars connecting the lower portions of said pairs of standards, a plurality of apertures formed in the longest 40 pair of said standards, yokes carried by each end of each of said connecting bars, each of said yokes provided with an aperture in its end, a locking pin extending through said aperture in each of said yokes and adapted to 45 be received by one of the apertures in said standards, and a run-way resting upon the connecting bars and provided with a plurality of transversely extending cleats.

In testimony whereof I affix my signature 50 in presence of two witnesses.

GEORGE WILLIAM KRAHMER.
